(57) **CLAIM**

The ornamental design for a combination of ties for retail display, as shown and described.

DESCRIPTION

FIG. 1 is a front perspective view of an embodiment of a combination of ties for retail display showing my new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; and, FIG. 7 is a bottom plan view thereof.

The hanger and trapezoid-shaped band shown in broken lines in the drawings are portions of the combination of ties for retail display that form no part of the claimed design.
